UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed November 6, 1922. Serial No. 599,221.

To all whom it may concern:

Be it known that I, ALFRED G. F. KUROWSKI, a citizen of the United States, residing in Brooklyn Borough, in the county of 5 Kings, city and State of New York, have invented certain new and useful Improvements in Typewriting Machines, of which the following is a specification.

This invention relates to typewriting machines, and more particularly to typewriting machines for typing bills for telephone service. In the operation of typing these bills, it is required to type separately the amounts of United States taxes. It is desirable at the same time to keep track of the total amount of the tax items for a day or other long period. This has been done heretofore by providing a standard typewriting machine with special "5" and "10" 10 keys to be used for no other purpose than the writing of tax items, and by providing registers for separately counting the operations of the special keys or for separately adding the items written by them.

25 A feature of the present invention is the provision, in a machine having special "5" and "10" keys for the purpose mentioned, of a single register and means for operating the register to cause it to add together the 30 items written by both of the special keys. This register is, in general, of the type of the well-known Veedee cyclometer, but has its units wheel especially arranged to enable it to count by five.

35 The invention is not limited in scope, however, to use in a machine provided with special keys for writing the tax items, nor to keys for writing any particular amounts, but may be applied to a machine having 40 only the usual complement of number-keys. It may also be used for other purposes than the writing of telephone bills and for obtaining the totals of items other than tax items.

45 The register is provided with an oscillatory operating arm arranged to cause an operation of the register each time it is oscillated, and connections are provided between the "5" and "10" keys and the operating arm to effect one oscillation of the operating arm when the "5" key is operated, and two oscillations of the operating arm when the "10" key is operated.

50 It is an important point that the register

is of the counter type, that is, of the type 55 having a wheel of lowest denomination arranged to be advanced at every operation of the register, and wheels of higher denomination arranged for operation only to carry over amounts run up on the wheel of lowest 60 denomination. A register of this type is cheap to manufacture and easy to operate at a type stroke.

Other features and advantages will hereinafter appear. 65

In the accompanying drawings,

Figure 1 is a side elevation of the front lower part of a typewriting machine having the present improvements applied thereto.

Figure 2 is a side elevation of the register 70 and its operating connections, showing the parts in the positions occupied by them when the "5" key has been partially depressed.

Figure 3 is a front sectional elevation of 75 the mechanism shown in Figure 1.

Figure 4 is a horizontal sectional view taken on the line 4—4 of Figure 1, but on a larger scale than Figure 1.

Figure 5 is a view similar to Figure 2, 80 showing the parts in the positions occupied by them when the "5" key has been fully depressed.

Figure 6 is a vertical sectional view on the line 6—6 of Figure 3, looking in the direction of the arrows, with the parts positioned at the end of an adding movement.

Figure 7 is a side elevation of one of the number-wheels of the register or counter other than the units wheel.

The typewriting machine comprises the 90 usual number and alphabet keys 11, and, in addition, a special "5" key 5 and a special "10" key 10, preferably arranged at the right-hand end of the keyboard, all of which keys operate types 12 to print in the usual 95 manner. A bracket 13, secured to the machine-frame 14, supports a register or counter 15 and connections between the register and stems 16 and 17 depending from the special "5" and "10" keys. These connections comprise a rock-shaft 18, borne in a bushing 19 carried by the bracket 13, and a rearwardly-extending crank-arm 20 on the rock-shaft 18. Headed studs 21 at the lower extremities of the stems 16 and 17 depending from the "5" and "10" keys overlie and engage the crank-arm 20 at distances 100 from the center of the rock-shaft 18 which

are so related to each other that a full depression of the "10" key rocks the shaft 18 through approximately twice the angle through which it is rocked by a full depression of the "5" key.

At its outer end the rock-shaft 18 has a second crank-arm 22, which is connected to operate a gear-segment 23, pivoted on the bracket 13, by means of a pin 24 on the crank-arm 22 and a slot 25 in the segment. The gear-segment meshes with and rotates a pinion 26 having a flange 27 upon which are mounted a pivoted pawl 28 and a spring 29 for pressing the pawl. A short shaft 30 mounted on the bracket 13 forms the bearing for the pinion 26 and also for a disk 31 having a single tooth 32. The spring 29 presses the pawl 28 against the toothed disk 31 to effect a one-way driving connection therewith. A crank 33 on the disk 31 is connected through a link 34 to oscillate a register-operating arm 35, the arrangement being such that each full revolution of the disk causes an oscillation of the arm 35. The parts are so proportioned and arranged that full depression of the "5" key oscillates the arm 35 once and full depression of the "10" key oscillates the arm 35 twice. A spring 36, connected to the tail of the operating arm 35 and to the bracket 13, maintains the operating arm normally at the advance limit of its movement. A spring 37, connected to the gear-segment 23 and to the bracket 13, returns the gear-segment to its normal elevated position, and, through the pinion 26, returns the pawl 28 independently of the toothed disk 31 and hence independently of the register-operating arm 35.

As has been stated, the register 15 is of the type of the Veeder cyclometer, but has its units wheel modified to adapt it to count by five. The register-operating arm 35 is connected with and oscillates a yoke 38, upon which is pivotally mounted a series of pawls 39 spring-pressed toward number-wheels 40 and 41 for co-operation with ratchet-teeth 42 thereon and with intervening shallow and deep notches 43 and 44 in the usual way, to advance the units wheel 40 one number-space at each full operating stroke of the yoke. Stops 45, for preventing overthrow of the wheels 40 and 41 and for locking them, are swung into and out of engagement with the wheels by the yoke 38. Spring-pressed pawls 46 engage the wheels 40 and 41 and prevent retrograde movement thereof. The units wheel 40 bears alternately the numerals "0" and "5", and has five deep notches 44 arranged alternately with five shallow notches 43. By this arrangement a carry-over operation onto the tens wheel of the register is effected at alternate operations of the register; that is, each time that the units wheel is advanced from "5" to "0". The wheels 41 of higher de-

nomination than the units wheel 40 are arranged with nine shallow notches 43 and one deep notch 44 as usual, so that each tenth operation of one of them will be effective to cause a carry-over operation onto the wheel of next higher denomination. It will be apparent that one full oscillation of the register-operating arm 35 will be effective to add five to the total exhibited by the register, and that two full oscillations of the register-operating arm will add five twice, increasing the total by ten.

The "5" key is shown in its fully-depressed position in Figure 5. In moving to this position, it moves the gear-segment 23 from the position of Figure 1, through the position of Figure 2, to that of Figure 5. The segment 23 turns the pinion 26 through one complete revolution in this movement, and the crank 33, through the pawl 28 and toothed disk 31, is turned in unison with the pinion, thus causing a complete oscillation of the register-operating arm 35, to add five to the total exhibited by the register. As the "5" key rises, the spring 37 raises the gear-segment 23, causing the pinion 26 to be rotated in the reverse direction. The pawl 28 moves with the pinion 26 in this movement, but the toothed disk 31 remains stationary, thereby permitting the crank 33 and the register-operating arm 35 to remain stationary also. The "10" key is arranged to rock the shaft 18 twice as far as the "5" key rocks it, and hence to depress the gear-segment 23 sufficiently to cause two complete revolutions of the pinion 26, and therefore two full oscillations of the register-operating arm 35, whereby ten will be added to the total exhibited by the register.

Variations may be resorted to within the scope of the invention, and portions of the improvements may be used without others.

Having thus described my invention, I claim:

1. In a typewriting machine, the combination of a pair of typing keys, a register for registering typed values, and means actuatable by one of the keys to register only once a certain amount and actuatable by the other key to register repeatedly the same amount.

2. In a typewriting machine, the combination of a pair of typing keys, one key to type a numeral and the other to type a multiple of that numeral, a register, and means actuatable by one of the keys to register a numeral and actuatable by the other key to register that numeral twice in succession.

3. In a typewriting machine, the combination of a set of keys for typing numbers, a pair of keys for typing special numerals, a single register, and means operable by the special keys, whereby one key will register its numeral once and the other key will register the same numeral twice in succession.

4. In a typewriting machine, the combination of a set of keys for general typing, a pair of keys for special typing, a register comprising number-wheels to count the typing values of the special keys, and means operable by the special keys, whereby one key will register a typed value once and the other key will register the same value twice in succession. 70
10. 5. In a typewriting machine, the combination of a set of numeral-keys for typing any numeral, a pair of special numeral-keys for typing special numerals, a register for registering the values of the special numerals typed, and means operable by the special keys, whereby one key will register its value by a single operation of the register and the other key will record its value by operating the register twice in succession. 75
15. 6. In a typewriting machine, a set of number keys for writing numbers, a plurality of special item keys for writing numbers, means comprising number wheels for adding the special items as they are written, an operating arm for said adding means having a uniform range of movement and capable in its full movement of advancing the number wheels one number space only, and connections between the special item keys and the operating arm for imparting operating movements to the arm in proportion to the amounts written by the respective special item keys. 80
20. 7. In a typewriting machine, two keys for writing numbers, one of which numbers is a multiple of the other, a register, an oscillating operating arm for operating the register by one full oscillation to add the smaller number to the total exhibited by the register, and connections between the key for writing the larger number and the operating arm to cause the depression of said key to oscillate the operating arm as many times as the smaller number is contained in the larger number. 85
25. 8. In a typewriting machine, the combination with a set of keys for general typing, of a pair of special keys for typing numerals, one numeral being a multiple of the other numeral, a counting register including number-wheels for registering typed amounts, an arm for operating the register uniformly, and means operable by the two special keys, whereby one key will operate the arm once to register a typed amount and the other key will operate the arm twice in succession to register a multiple of the first amount typed. 90
30. 9. In a typewriting machine, the combination with a register for counting operations, of a vibratory arm to operate the register, a pair of keys, and key-actuated mechanism whereby one key will vibrate the arm once and the other key will vibrate the arm twice in succession to operate the register. 95
35. 10. In a typewriting machine, the combination with a register for counting operations, of an arm to operate the register, a set of keys, and connections between the arm and the keys whereby one key will operate the arm to register once and the other key will operate the arm to register twice in succession. 100
40. 11. In a typewriting machine, the combination with a register for counting typing operations, of an arm to operate the register at each movement thereof, a set of keys, and means for causing the arm to be operated once by one of the keys and to be operated twice in succession by the other key. 105
45. 12. In a typewriting machine, two number keys movable downward to write numbers and movable upward to return to their normal positions, a register arranged for operation by the number keys, an oscillatory register operating arm, and means operated by the number keys for causing the operating arm to be fully oscillated once during movement of one of the keys in a single direction and to be fully oscillated a plurality of times during movement of the other key in a single direction. 110
50. 13. In a machine of the kind described, a number key for writing the number "5", a number key for writing the number "10", the keys being movable in one direction to write the numbers and in the other direction to return to their normal positions, a register arranged for operation by the number keys, an oscillatory register operating arm, and means operated by the number keys for causing the operating arm to be fully oscillated once during movement of the "5" key in a single direction and to be fully oscillated twice during movement of the "10" key in a single direction. 115
55. 14. In a machine of the kind described, a number key for writing the number "5", a number key for writing the number "10", a register arranged to count by five, and means for causing the register to be operated once by the operation of the "5" key and to be operated twice by the operation of the "10" key. 120
60. 15. In a machine of the kind described, a number key for writing the number "5", a number key for writing the number "10", the keys being movable in one direction to write the numbers and in the opposite direction to return to their normal positions, a register arranged to count by five, and means for causing the register to be operated once during movement in a single direction of the "5" key and to be operated twice during movement in a single direction of the "10" key. 125
65. 16. In a machine of the kind described, a number key for writing a number, a num- 130

- ber key for writing a multiple of said number, a register arranged to count by the smaller number, and means for causing the register to be operated once by the operation 5 of the key for writing the smaller number and to be operated by the operation of the key for writing the larger number as many times as the smaller number is contained in the larger number.
- 10 17. In a machine of the kind described, a number key for writing a number, a number key for writing a multiple of said number, a register arranged to count by the smaller number, and means for causing the register 15 to be operated once by the operation of the key for writing the smaller number and to be operated by the operation of the key for writing the larger number as many times as the smaller number is contained in the larger 20 number, the register operating means being arranged to effect said operations of the register during movements of the respective number keys in one direction and to permit the register to remain idle during movements of the keys in the opposite direction.
18. In a typewriting machine, a plurality of number keys, a counter operated by the keys, and counter operating connections comprising a crank-arm operatively engaged 30 by said number keys so that one key will operate the arm once and another key will operate the arm twice.
19. In a typewriting machine, a plurality of number keys, a register operated by the 35 keys, an oscillatory register operating arm, and connections between the number keys and the register operating arm comprising a rock-shaft, means fixed to the rock-shaft for rocking the shaft and separably engaged by the number keys for depression different 40 distances by them independently of each other, and means for causing one or more oscillations of the register operating arm when the rock-shaft is rocked according to 45 the extent of the rocking movement.
20. In a typewriting machine, means for writing the numbers "5" and "10" in a certain location, and means for adding the 50 items so written comprising a register, an oscillatory register operating arm, and means for oscillating the operating arm once when "5" is so written and twice when "10" is so written.
21. In a typewriting machine, a plurality 55 of number keys for writing different numbers, a register comprising number wheels, an operating arm for advancing the units wheel one number space at every operation, and means operated by the number keys to 60 operate the arm once with one key to add a unit to the total exhibited by the number wheels of the register, and operate the arm twice by another key to add a double unit to the total exhibited.
- 65 22. In a machine of the kind described, a

number key, a register arranged for operation by the number key, an oscillatory register operating arm, and connections between the number key and the register operating arm arranged to cause the register operating arm to be oscillated a plurality of times by a single operation of the number key. 70

23. In a typewriting machine, a number key movable downward to write a number 75 and upward to return to normal position, a register arranged for operation by the number key, an oscillatory register operating arm, and means operated by the number key for causing the operating arm to be operated a plurality of times during one of said movements of the number key. 80

24. In a typewriting machine, a number key movable in one direction to write a number 85 and in the opposite direction to return to normal position, a register arranged for operation by the number key, an oscillatory register operating arm, and means operated by the number key for causing the operating arm to be fully oscillated during 90 movement of the number key in a single direction.

25. In a typewriting machine, a number key movable in one direction to write a number 95 and in the opposite direction to return to normal position, a register arranged for operation by the number key, an oscillatory register operating arm, and means operated by the number key for causing the operating arm to be operated during movement of the number key in a single direction and to remain idle during movement of the number key in the opposite direction. 100

26. In a typewriting machine, a number key, a register operated thereby, an oscillatory register operating arm, and register operating connections between the number key and the register operating arm for oscillating it, comprising a rotary member arranged to fully oscillate the register operating arm by one full rotation and means for rotating said member. 105

27. In a typewriting machine, a number key, a stem depending from said number key, a crank-arm engaged by said stem, a rock-shaft on which the crank-arm is fixed, a second crank-arm fixed to the rock-shaft, a gear segment, pin-and-slot connections between the second crank-arm and the gear segment for depressing the gear segment when the number key is depressed, a spring for restoring the gear segment to normal position, a pinion in mesh with said gear segment, a pawl carried by said pinion, a shaft upon which the pinion is rotatably mounted, a toothed disk on the shaft engaged by the pawl, a crank on the disk, a link connected to the crank, an arm connected to the link, and a register arranged for operation by the arm. 115

25

30

35

40

28. In a typewriting machine, a number key, a register, a gear segment movable in one direction by the number key, a spring for moving the gear segment in the opposite direction, a pinion constantly in mesh with the gear segment, register operating mechanism, and means connecting the pinion with the register operating mechanism to operate said mechanism when the pinion is rotated in one direction and to permit the pinion to rotate independently of said mechanism in the opposite direction.
29. In a typewriting machine, a number key, a counter, a member movable in one direction by the number key, means for automatically moving said member in the opposite direction when the number key is released, oscillatory counter operating mechanism, and means for connecting the member with the counter operating mechanism to oscillate said mechanism when the member is moved in one of said directions and to permit said mechanism to remain stationary when the member is moved in the other direction.
30. In a typewriting machine, a pair of keys, and means actuatable by an operation of one of the keys to oscillate an arm once and actuatable by the other of the keys to oscillate the arm twice.
31. In a typewriting machine, a pair of number-keys, a crank beneath the number-keys, a rock-shaft on which the crank is fast, a gear segment on the rock-shaft, a pinion in mesh with the gear segment, a one-way drive between the pinion and a rotary shaft, and a rod connecting the rotary shaft to an oscillatory counter-operating arm, whereby the counter-operating arm will be oscillated once at the depression of one of the keys and permitted to remain idle on the return stroke thereof, and will be oscillated twice at the depression of the other key and permitted to remain idle on the return stroke of the latter.

ALFRED G. F. KUROWSKI.
